UNITED STATES PATENT OFFICE

WENZEL J. DVORAK, OF HOUSTON, TEXAS

CONCRETE CONSTRUCTION

Application filed February 17, 1930. Serial No. 429,070.

This invention relates to new and useful improvements in concrete construction.

One object of the invention is to provide an improved type of concrete construction 5 wherein pre-cast slabs may be assembled and tied to the supporting girders, or framework, in a novel manner, said framework, in the main, being formed of concrete and cast in place.

10 Another object of the invention resides in a novel type of concrete construction specially adapted for use in the construction of roofs, floors, walls, stairways and the like and embodying the use of pre-cast units, connected together, and to the structure, in a novel way.

With the above and other objects in view this invention has particular relation to certain novel features of construction, arrangement of parts, and use, an example of which is given in this specification and illustrated 20 in the accompanying drawing, wherein:—

Figure 1 shows a plan view of the slabs employed, shown connected together.

25 Figure 2 shows a cross sectional view taken on the line 2—2 of Figure 1.

Figure 3 shows a cross sectional view taken on the line 3—3 of Figure 1.

Figure 4 shows an edge view of a slab.

30 Figure 5 shows a longitudinal sectional view taken on the line 5—5 of Figure 1.

Figure 6 shows a fragmentary front elevation of a stairway embodying the invention.

35 Figure 7 shows a fragmentary cross sectional view taken on the line 7—7 of Figure 6.

Figure 8 shows a fragmentary plan view of said stairway, partly in section, and

Figure 9 shows a fragmentary side elevation thereof.

40 Referring now more particularly to the drawing, wherein like numerals of reference designate similar parts in each of the figures, the numerals 1 designate concrete slabs, preferably rectangular in form. These slabs are 45 pre-cast and preferably have smooth upper surfaces. Each slab, at one edge, has an offset forming a V-shaped groove 2 from end to end thereof and at its other edge has a lengthwise marginal rib 3. Spaced apart along 50 each slab are reinforcing rods as 4 which are

embedded in the material thereof and which are formed with the loops 5 projecting into the corresponding grooves 2 and also the loops 6 which project out through the corresponding rib 3. The grooved margins of the slab also have the marginal thickened ribs 7 and the reinforcing rods 4 are formed also into the loops 8 in said ribs 7 and there are the lengthwise reinforcing rods 9 extending through the ribs 7 within said loops 8. Each slab 1 also has the marginal dowel pins 10 at one margin, adapted to be inserted into corresponding sockets 11 in the adjacent margin of the adjoining slab, said dowel pins serving to hold said slabs in alignment during the process of erection. The slabs also have suitable lengthwise reinforcing rods 12 therethrough which are formed into the projecting end loops 13.

55 In erecting the slabs into the structure said slabs are placed in their proper position in which position they are held by suitable temporary framework (not shown). In this position the marginal loops 5, 6 overlap in the grooves 2 and the end loops 13 also register or overlap. The ends of the respective tiers of slabs are spaced apart and, during the process of erection the girders as 14 are poured in place while in plastic state. Previous to pouring said girders suitable tie rods 80 as 15 are inserted through said overlapping loops 13 and are surrounded by suitable reinforcing rings 16. When the girders are 75 poured the reinforcing consisting of the rods 15 and the rings 16, are completely embedded 85 therein and the loops 13 serve to tie the slabs to the supporting girders. The overlapping loops 5, 6, in the respective grooves 2, are tied together by the tie rods 13 which are 90 inserted therethrough and said grooves 2 are then filled with plastic concrete which embeds said loops and tie rod therein and the concrete material filling said grooves is then smoothed off flush with the surface of the slabs.

95 In Figures 6 to 9, inclusive, the invention is shown as applied to the erection of stairways wherein the numeral 18 designates the supporting masonry and the numeral 19 designates the finishing precast slabs shaped 100

- so that when erected suitable steps will be thereby formed as illustrated in Figure 7; each pre-cast slab 19 has spaced transverse rods 20 embedded therein and projecting at 5 the rear margin of the tread forming the up-standing loops 21. At the lower inside margin of the riser of each slab 19 there is a transverse groove 22 into which the up-standing loops 21 extend and the rods 20 are also 10 formed into loops 23 in said grooves 22 which overlap the upstanding loops 21 and tie rods 24 are inserted through said overlapping loops to tie the tread of each step slab to the riser of the slab above. Embedded in and 15 projecting from the masonry of the foundation 18, which forms an anchor, are the anchor loops 25 which surround the respective upstanding loops 21 and anchor the step slabs in place.
- 20 The drawing and description disclose what I now consider to be a preferred form of the invention by way of illustration only, while the broad principle of the invention will be defined by the appended claims.
- 25 What I claim is:
1. A concrete construction formed of concrete slabs, the adjacent edges of said slabs being provided, one with a thickened rib having a longitudinal groove in which the 30 adjacent margin of the other slab projects, said adjacent margins also having projecting loops which overlap and tie rods fitted through said overlapping loops to secure adjacent slabs together.
  - 35 2. A concrete construction for forming plane surfaces and formed of concrete slabs, the adjacent edges of said slabs being formed, one with a lengthwise groove into which the other projects, transverse reinforcing rods 40 spaced apart in each slab said rods of said slabs projecting into said groove and being formed into overlapping loops, a tie rod in said groove fitted through said overlapping loops and tying said slabs together, the adjacent 45 edges of adjoining slabs being provided one with a dowel and the other with a bearing to receive said dowel and lengthwise reinforcing rods in each slab around which said transverse bars are looped.
  - 50 3. A concrete construction formed of united concrete slabs, the adjacent edges of said slabs having projecting loops which overlap and tie rods fitted through said overlapping loops to secure adjacent slabs together, the adjacent 55 edges of adjoining slabs being provided, one with projecting dowels and the other with bearings to receive said dowels to maintain said slabs in alignment.
  - 60 4. A concrete construction formed of pre-cast slabs arranged with their margins adjacent, spaced transverse reinforcing rods embedded in each slab and projecting outwardly at one margin and formed into loops, the adjacent margin of the other slab being 65 cessed to receive said loops, the reinforcing

rods of each slab being also formed into loops in the recessed portion of said slab, said loops in said recesses overlapping, tie rods extending through said overlapping loops, anchor rods embedded in a stationary anchor and end loops at the ends of the slabs surrounding the anchor rods and securing said slabs to said anchor.

5. In a concrete construction for floors and the like, a concrete slab having one margin thickened forming a longitudinal rib and reinforcing transverse ribs extending from said marginal rib toward, but falling short of the opposite margin of the slab, said longitudinal rib, and cross ribs being formed integrally with the slab.

6. In concrete construction a slab thickened at one margin forming a longitudinal rib, said slab having a longitudinal groove at said margin, cross ribs extending from said longitudinal rib toward, but falling short of the opposite margin of the slab, reinforcing rods embedded in the material of the slab, and formed into loops which project into said groove at one margin of the slab and also formed into projecting loops at the opposite margin of the slab.

7. In concrete construction a slab having a longitudinal marginal rib formed with a longitudinal recess, a reinforcing rod embedded in the material of said slab and formed with a loop which projects into said recess and said rod being also formed with a projecting loop at the opposite margin of the slab which projects at substantially right angles to the plane of the slab.

8. A cementitious slab having an approximately plane upper surface and being thickened at one margin to form a depending longitudinal rib, said margin also having a longitudinal groove, depending, transverse ribs, spaced apart, and formed integrally with the slab and with the marginal rib thereof, said transverse ribs falling short of the other margin of the slab, transverse reinforcing rods in said slab which terminate in loops in said groove and in loops which project from the opposite margin of the slab.

In testimony whereof I have signed my name to this specification.

WENZEL J. DVORAK.
